(57)

CLAIM

The ornamental design for footwear, as shown and described.

DESCRIPTION

FIG. 1 is a front perspective view of a shoe showing my new design;

FIG. 2 is a right side view thereof;

FIG. 3 is a left side view thereof;

FIG. 4 is a rear view thereof;

FIG. 5 is a front view thereof;

FIG. 6 is a top view thereof; and,

FIG. 7 is another perspective view thereof.

The broken line showing of the heel, heel cap and sole in the drawings shows unclaimed subject matter.

1 Claim, 7 Drawing Sheets(56)
